UNITED STATES PATENT OFFICE.

ROBERT M. GALLOWAY AND ALFRED G. SUDHOFF, OF RICHMOND, INDIANA, AS-
SIGNORS TO THE NATIONAL AUTOMATIC TOOL COMPANY, OF RICHMOND, INDIANA,
A CORPORATION OF INDIANA.

ROTARY TABLE FOR DRILLING MACHINES.

Application filed February 26, 1923. Serial No. 621,163.

To all whom it may concern:

Be it known that we, RORERT M. GALLOWAY and ALFRED G. SUDHOFF, citizens of the United States, residing at Richmond, in the 5 county of Wayne and State of Indiana, have invented certain new and useful Improvements in Rotary Tables for Drilling Machines, of which the following is a specification.

10 Our invention relates to rotary tables such as used with drilling machines, an example of which may be seen in the patent granted February 8, 1921, No. 1,367,579, on an invention of William M. Ziegler and 15 Alfred G. Sudhoff. There is a showing in this patent of means for raising the table off of its seat or track and for indexing it, such means taking the form of two separate levers, one of them serving to lift the table 20 and the other to unlock it.

The main object of our present invention is to much simplify the table lifting and indexing mechanism and in carrying out this object we dispense with the necessity for 25 two separate appliances such as the levers just mentioned and provide for the lifting of the table and its unlocking by one and the same act. Thus a single lever or treadle serves for both purposes and the operator 30 has his hands that much freer for simultaneously performing other manipulations.

In the drawings which accompany and form part of this specification, Fig. 1 represents a top plan view of a table having our invention applied to it in one form, the top of the table and part of the base being broken away and some portions shown in horizontal section for the better portrayal of the invention; Fig. 2 is a vertical section taken on the line 2—2 of Fig. 1; Fig. 3 is another vertical section taken at right angles to Fig. 2 on the line 3—3 of Fig. 1; Fig. 4 is a view similar to Fig. 3 showing a somewhat different form of embodiment of the 45 invention; Fig 5 is a fragmentary sectional plan view taken substantially on the line 5—5 of Fig. 4; Fig. 6 is a detached perspective view of the head of a latch for the indexing bolt employed in the construction illustrated by Figs. 1 and 3; and Fig. 7 is a fragmentary elevation illustrating a further modification.

The numeral 2 designates the fixed base of the structure which is of skeleton form

and has at the center a bearing 3 receiving the journal stud 4 of the table 5. The base has a track or seat 6 which encircles the central bearing and the table has a circular foot formation 7 to rest upon said track or seat so that the table will be evenly and 60 solidly supported when work is on it and being operated upon. The journal stud 4 is slidable up and down in the bearing 3 so that the table may be lifted off of its seat when it is to be rotated. For indexing 65 purposes a series of sockets 8 are formed in the foot portion of the table and preferably bushed, and the base is formed with a boss 9 with a bushing in which a bolt is vertically slidable for entrance into and 70 withdrawal from these sockets.

The central journal stud 4 is recessed in its under-side for the accommodation of a single anti-friction ball 10 which seats in the similar recess of a hardened block 11 75 set in the short inner arm of a lever 12. The latter is pivoted at 13 in the base of the apparatus and its longer arm extends outwardly and is coupled to an operating lever extending at right angles to it. Obviously 80 depression of the long arm of this lever 12 will result in lifting the table upon the ball bearing so that the table will be free from the track or seat and may be easily turned.

Thus far the construction is the same in 85 both illustrated forms of embodiment of the invention. Referring now more particularly to Figs. 1 and 3, the operating lever is designated 14, the same being pivoted at its inner end to the base, as shown at 90 15. This lever is coupled to the table-lifting lever 12 adjacent the pivot 15 by a shackle bolt 16, the eye of which engages a cross-pin in the lever 14 and the shank of which extends through the long arm of 95 the lever 12 and receives a nut over a washer and bearing block, the latter of semi-spherical form and engaging a complementary socket formed in the lever. The operating lever 14 extends outwardly beyond the table where it has a handle 15' and it will be obvious that by pressing down on that handle the table may be lifted in the manner already mentioned. The indexing bolt is designated by the numeral 17 and it 105 extends freely through an opening 17' in the lever 14. It is bored out to receive a compression spring 18 which is confined in

a suitable seat 19 on the base of the apparatus and which serves to thrust the bolt upwardly for engagement with the indexing socket of the table. Corresponding 5 angular slots 20 are formed in opposite sides of this hollow bolt and the lever 14 carries a latch normally engaging the short horizontal upper portions of these slots so that when the lever 14 is depressed the bolt 17 10 will be carried down with it and so withdrawn from the table socket. This latch comprises a head 21 and a stem 22 occupying a recessed under portion of the lever 14 closed in by a cover plate 23. The head 15 21 is forked to straddle the bolt 16 and its arms have studs 24 (Fig. 6) to extend into the slots 20. A spring 25 is put around the latch stem 22 between the head 21 and an internal shoulder of the lever 14 and serves 20 to keep the studs 24 normally in the horizontal portions of the slots. The latch stem is coupled at its outer end to a latch lever 26 pivotally suspended from the outer portion of the operating lever 14. 25 Still referring to the form of construction illustrated by Figs. 1, 3 and 6, when occasion arises for rotating the table as for the proper positioning or re-positioning of work upon it under the drills of a drilling 30 machine, the operator has merely to push down the outer end of the operating lever 14, thereby lifting the table in the manner already described and at the same time withdrawing the bolt 17 from the table 35 socket. Then with the same hand he will operate the latch lever 26, having started to turn the table with his other hand, and this working of the latch lever will draw the latch outwardly and bring its studs 24 40 in line with the vertical portions of the slots 20 whereupon the spring 18, which was of course compressed when the bolt was forced down, will drive the bolt upwardly against the foot portion of the table ready to spring 45 into the next socket as soon as the table has been turned the corresponding distance. Of course the studs 24 do not leave the slots 20 and therefore as soon as the lever 14 is released and rises with the dropping of the 50 table onto its seat these studs travel up the slots 20 and, the latch lever 26 having been released, spring 25 will throw the studs into the horizontal portions of the slots so that the normal condition is restored. 55 Referring next to the further simplified construction illustrated by Figs. 4 and 5, the operating lever is designated by the numeral 30 and is coupled to the lever 12 in just the same way as already described in 60 connection with the other form of construction. The difference between the two constructions has to do with the relationship between the operating lever and the indexing bolt. The latter is here designated 31 65 and, unlike the bolt of the first described

construction, it does not have vertical movement independently of the operating lever, but is permanently coupled to the latter so as to move up and down with it. To this end the bolt, where it extends through the 70 lever, is formed with a cross slot or notch 22 in one side, and a bolt 33 is run crosswise through the lever as best shown in Fig. 5 so as to occupy said notch, sufficient play being allowed for, to accommodate the arc 75 of movement the lever. In this construction the bolt does not have a spring applied directly to it; its lower end simply slides in a boss formed on the bottom part of the base. Between the bolt and the pivot 80 of the operating lever a spring 35 is directly applied to the lever, being received at the upper end in a recess of the lever and at the lower end in a recess on the base. This is a compression spring like the spring 18 of 85 the first described construction and it functions to keep the parts of the table lifting and indexing mechanism in proper normal state with the bolt in the table socket. Quite 90 obviously a spring might be otherwise applied for the purpose, as e. g., by extending the same between the lever and the overhanging portion of the base in the manner shown by Fig. 7 wherein the spring is designated 35^a and engages at one end in an 95 eye-lug on the base and at the other end with a stud on an ear of the lever.

It will be seen that in the use of the last described form of embodiment of the invention depression of the outer end of the 100 operating lever 30 will lift the table off its seat the same as in the case of the first described construction and will simultaneously withdraw the indexing bolt from the table socket and that this will be done in 105 opposition to the spring 35 but in this simplified construction there is no additional operation such as the working of a latch. As soon as the table is started in rotation 110 the lever 30 may be released and being moved upward by the weight of the table and also the expansion of the spring 35 will carry with it the bolt 31 so that the latter will be pressing against the foot 115 portion of the table ready to instantly enter the next socket therein. As soon as that occurs the table again drops upon its seat.

Either form of construction above described fulfills the object primarily stated 120 and it is to be understood that the invention may be embodied in still different forms within the scope of claims which follow:

We claim:

1. The combination of a base, a table mounted to rotate over said base and to rest upon the same, means for holding the table at different positions of rotation, means for lifting the table off its seat, and means for operating said lifting means with provisions for also releasing the table from its 125 130

holding means by operation of said lifting means.

2. The combination of a base, a table mounted to rotate over said base and to rest upon the same, and having a series of indexing sockets, a bolt for engaging the same to hold the table at different positions of rotation, means for lifting the table off its seat, and means for operating said lifting means with provisions for also withdrawing the bolt by operation of said lifting means.

3. The combination of a base having a central bearing and an encircling track, a table having a journal stud occupying said bearing and a series of sockets over the base track, a bolt to engage said sockets, a lever extending under the table stud, and another lever engaging the first mentioned one for operating the same to lift the table, said second lever also engaging the bolt to withdraw it from the table-socket.

4. The combination of a base having a central bearing and an encircling track, a table having a journal stud occupying said bearing and a series of sockets over the base track, a bolt mounted to slide vertically in the base and engage the sockets in the table, a lever permanently engaged with said bolt for moving it up and down, and connections for lifting the table simultaneously with retraction of the bolt.

5. The combination of a base having a central bearing and an encircling track, a table having a journal stud occupying said bearing and a series of sockets over the base track, a bolt mounted to slide vertically in the base and engage the sockets in the table, a lever permanently engaged with

said bolt for moving it up and down, a spring applied to the lever, and connections for lifting the table simultaneously with retraction of the bolt.

6. The combination of a base having a central bearing and an encircling track, a table having a journal stud occupying said bearing and a series of sockets over the base track, a bolt mounted to slide vertically in the base and engage the sockets in the table, a lever pivoted beneath the table and extending under the latter's journal stud on one side of its pivot, a second lever extending at right angles to the first and coupled to the latter on the other side of its pivot, and a permanent connection between the bolt and the second lever on the same side of the latter's pivot as the coupling between the two levers.

7. The combination of a base having a central bearing and an encircling track, a table having a journal stud occupying said bearing and a series of sockets over the base track, a bolt mounted to slide vertically in the base and engage the sockets in the table, a lever pivoted beneath the table and extending under the latter's journal stud on one side of its pivot, a second lever extending at right angles to the first and coupled to the latter on the other side of its pivot, a permanent connection between the bolt and the second lever on the same side of the latter's pivot as the coupling between the two levers, and a compression spring below the second lever also on that same side of its pivot.
